Primary Examiner — Cathron Brooks*Assistant Examiner* — Sydney R Buffalow(74) *Attorney, Agent, or Firm* — Michael J. Weins; Jeffrey E. Semprebon(57) **CLAIM**

The ornamental design for a slat-wall shelf cover, as is shown and described.

DESCRIPTION

FIG. 1 is a perspective view showing a slat-wall shelf cover of my new design when resting atop a slat-wall shelf so as to form a shelf in a cabinet environment.

FIG. 2 is an upper perspective view thereof when removed from the slat-wall shelf shown in FIG. 1.

FIG. 3 is a lower perspective view of thereof when resting atop a slat-wall shelf.

FIG. 4 is a front elevation view thereof. The rear elevation view is not visible when the shelf cover is in use.

FIG. 5 is a right side elevation view thereof. The left side is a mirror image of the right side.

FIG. 6 is a top plan view thereof.

FIG. 7 is a bottom plan view thereof, shown when the shelf cover rests atop a slat-wall shelf; and,

FIG. 8 is a view the section 8-8 of FIG. 6.

The broken lines in FIGS. 1, 3, 7, and 8 show the environment of the shelf cover and/or functional features of the article that allow it to interact properly with the environment; these elements do not form a part of the claimed design.
